PORTABLE COFFEE DISPENSER

John C. Gardner, Horicon, Wis., assignor to Gardner Manufacturing Company, Horicon, Wis., a corporation of Wisconsin

Filed July 11, 1960, Ser. No. 61,302

Term of patent 14 years

(Cl. D52—3)

The figure is a view in perspective of a portable coffee dispenser embodying my new design. The sides of the cabinet which are not shown in the drawing are plain.

The lining on the inset panel represents a contrasting surface. The condiment dispensers shown in broken lines are included for illustrative purposes only.

I claim:

The ornamental design for a portable coffee dispenser, as shown and described.
